UNITED STATES PATENT OFFICE.

OTIS ALLEN, OF NEWARK, OHIO.

AUTOMATIC GREASE-CUP.

No. 910,346.

Specification of Letters Patent.

Patented Jan. 19, 1909.

Application filed January 23, 1908. Serial No. 412,349.

To all whom it may concern:

Be it known that I, OTIS ALLEN, a citizen of the United States, residing at Newark, in the county of Licking and State of Ohio, 5 have invented certain new and useful Improvements in Automatic Grease-Cups; and I do hereby declare the following to be a full, clear, and exact description of the invention, such as will enable others skilled in the art 10 to which it appertains to make and use the same.

My invention relates to new and useful improvements in automatic grease cups and more particularly to that class adapted to 15 be used for feeding lubricant to journals and my object is to provide a device of this class, whereby the flow of the lubricant will be uniform at all times.

A further object is to provide means for 20 readily and quickly attaching the grease cup in position.

A still further object is to provide means for retaining the feeding plunger at one end 25 of the cup, while the cup is being filled with the lubricant and a still further object is to provide means on the cup whereby the cup may be used in connection with sockets of different sizes.

Other objects and advantages will be 30 hereinafter referred to and more particularly pointed out in the claim.

In the accompanying drawings which are made a part of this application, Figure 1 is a vertical, sectional view through one end of a 35 driving rod and journal of that class used in connection with railway locomotives showing my improved grease cup operatively attached thereto. Fig. 2 is a side elevation of the grease cup removed, Fig. 3 is a top plan view thereof, and, Fig. 4 is a sectional view 40 of the body of the cup, showing the manner of forming the band thereon.

Referring to the drawings in which similar reference numerals designate corresponding 45 parts throughout the several views, 1 indicates a driving rod, such as is commonly used in connection with railway locomotives, to the ends of which are secured straps 2, said straps being secured to the driving 50 rod in any preferred manner, as by introducing bolts 3 through the straps and the interposed portions of the driving rod. The closed ends of the straps 2 extend beyond the ends of the driving rod and provide a 55 seat for the usual form of bearing brasses 4, said brasses being formed in two sections

and having semi-circular cavities 5 in their meeting faces, through which extends the journal 6. The meeting faces of the brasses 4 are slightly spaced apart, whereby said 60 brasses may be adjusted towards each other to compensate for any wear thereon and to better accomplish this result, the ends of the driving rod 1 are slightly tapered and a wedge 7, having a tapered face to coöperate 65 with the taper of the end of the driving rod, introduced between the driving rod and bearing brasses, the wedge being of less length than the distance between the two arms of the strap and having a threaded 70 opening 8 extending longitudinally thereof, through which extends a threaded bolt 9 and it will be readily seen that when the bolt is rotated in one direction, the wedge 7 will be gradually drawn upwardly and the 75 brasses moved towards each other, thereby taking up the wear of the brasses and preventing knocking of the driving rod on the journals.

It has been found in practice that by solidifying the lubricant, it can be more systematically fed to the journals, and by so preparing the lubricant, it requires a special grease cup for holding the same, this form of oil cup being threaded into a socket 10 extending upwardly from the straps 2, and in using the form of grease cup now commonly employed, unless great care is exercised in removing the cup or introducing the same into the socket, the threads on the interior of the socket become mutilated, and in view of the prevalence of such mutilation, the sockets have heretofore been lined with bushing, so that said bushing could be removed and renewed when the threads become mutilated. This manner of attaching the grease cups, however, necessitates a great deal of expense, and to this end I have provided my improved form of grease cup, comprising a cylindrical body 11, which is open at its lower end, that portion of the body employed for closing the end of the body, being formed into a nut 12, whereby a wrench may be readily applied to the cup for removing or securing the same to the socket. The outer face of the body 11 is 100 provided substantially at its longitudinal center with a band or extension 13, the outer face of said band having threads 14 formed thereon, which are adapted to engage threads 15 on the interior of the socket 10, said 105 threads 15 being preferably limited to the upper portion of the socket.

It has been the custom heretofore in constructing sockets to receive the grease cups, to line said sockets with bushing, as the threads on the interior of the sockets are frequently broken or mutilated, so that the threads on the cup will not hold, in which event it becomes necessary to remove the bushing having the mutilated threads and place a new bushing in the socket and it has also been found that frequently the cups become stuck, so that in removing the same, the bushing is twisted loose from the wall of the socket, and to overcome these objectionable features, and at the same time enable me to produce a cup at a minimum cost, I have provided the band or extension on the cup and entirely dispensed with the bushing and placed threads directly on the wall of the socket.

When the cups are cast, the bands are formed of a much larger diameter than is necessary to fit standard sized sockets, so that should the threads on the wall of the socket become broken or otherwise destroyed, the socket may be reamed out to remove the broken threads and new threads placed therein, this operation enlarging the interior of the socket, so that the bands on the cups, turned down to fit the standard sized sockets, will be too small for the enlarged socket, but by providing the enlarged bands, a new cup is employed in connection with the enlarged socket and the band thereon turned down and provided with threads to fit the enlarged socket, while the cup originally fitted to the socket may be transferred to another socket of a standard size. This operation may be repeated any number of times or until such time as the wall of the socket becomes too thin to receive additional threads, as the collars, when originally prepared, are to be of such diameter as to fit the largest opening that could be made in the socket and as these bands are formed in blank, the faces of said bands may be readily turned down to fit the opening in the socket and then provided with threads to engage the threads on the interior of the socket. It will likewise be seen that should the threads on the cups become broken, except those of course which were originally prepared to fit the standard sized socket, said broken threads may be likewise removed from the band and said band turned down to fit a socket of a smaller size and again supplied with new threads. It will further be seen that the cups may be used until completely worn out, as should the threads in the socket to which the cup has been fitted, become destroyed, said cup may be transferred to another bearing having a socket of such diameter as to receive the threads on the cup, while the socket from which the cup has been removed, is to be reamed out and rethreaded and a cup entered therein having a band thereon of sufficient

diameter to fit the enlarged socket or if a cup is not to be found, the collar on which will fit the enlarged socket, a new cup is brought into use and the band turned down to fit said socket.

The closed end of the body 11 is provided with a central opening 16, through which extends a plunger 17, the lower end of said plunger being provided with a piston 18, the peripheral face of which is provided with a recess to receive any suitable form of packing 19, thus preventing the lubricant from passing between the piston and the wall of the body. The plunger 17 is of sufficient length to extend slightly above the closed end of the body when the piston is in its lowest position and is provided adjacent its upper end with a cross arm 20, which arm is adapted to be used in moving the piston towards the closed end of the body, as well as to serve as an indicator to show when the body is practically empty, the close proximity of the cross arm to the top of the nut 12 indicating that the body should be replenished with lubricant.

In preparing the lubricant, it is preferably made into stick form of sufficient diameter to snugly fit into the body 11, one end of the stick of lubricant resting on the base 21 of the socket 10, while the piston 18 rests on the opposite end thereof and in order to uniformly feed the lubricant through a port 22 in the strap 2, a spring 23 is coiled around the plunger 17 between the closed end of the body 11 and the piston 18, the tension of said spring being so regulated that the lubricant will not be fed through the port 22 faster than it is consumed by the journal, the lubricant, after leaving the port 22, passing between the meeting faces of the brasses 4 onto the journal 6.

To prevent the spring from moving the piston to the open end of the body, while the cup is being filled with lubricant, a lug 24 is provided on the plunger 17, which is adapted to extend over and engage the upper face of the nut 12, while the cup is being filled and to be returned to the socket through a channel 25 formed in the nut 12, which is of sufficient width to snugly receive the lug 115 and the lug is so located on the plunger 17 as to register with the outer face of the nut when the piston 18 is moved to its uppermost stroke, so that by giving a slight turn to the plunger after it has been moved its full distance, the lug will be moved out of registration with the channel and over the face of the nut, thereby holding the piston adjacent the closed end of the body until the plunger is again rotated and the lug brought into 125 registration with the channel when the tension of the spring will force the piston against the lubricant and feed the lubricant to the journal.

In applying the grease cup to use, the

plunger 17 is moved outwardly through the opening 16 its full stroke when the plunger is slightly rotated to extend the lug 24 over the top of the nut 12 when the stick of lubricant is inserted in the open end of the cylindrical body and the cup then entered into the socket 10, the body being turned into the socket until the lower end of the body is firmly seated against the base 21, the forcing 10 of the end of the body against the base, serving as a lock to prevent the cup from casual removal from the socket, thereby dispensing with the usual form of lock-nut usually employed for this purpose. The plunger 17 is then given a reverse rotation until the lug is again brought into registration with the channel 25 when the spring will exert pressure on the piston and lower the piston into positive engagement with the stick of lubricant, the downward movement of the piston being sufficient to enter the lug in the channel and it will be readily seen that as the lubricant is consumed by the journal, the tension of the spring will gradually force a 25 new supply of lubricant through the port 22 into engagement with the journal, said lubricant being continuously and uniformly fed until the stick of lubricant has been entirely consumed. It will further be seen 30 that by forming the body of the cup with an exterior band or extension of such diameter as to fit the largest sized opening that could be made in the socket or turned down to fit various sized smaller sockets on 35 the straps, the usual form of bushing now employed to receive the threaded portion of the cup, may be dispensed with, which is a very important item, as it frequently occurs in attempting to remove the cup, that the

bushing becomes loosened from the wall of 40 the socket, thereby requiring a great deal of time and labor in removing the cup, as well as the destruction of the bushing.

What I claim is:

In combination with a driving rod, straps 45 thereon and brasses within the straps, said straps having a port therein communicating with the space between the opposed faces of the brasses; of an annular flange formed with the straps around the port a distance 50 therefrom, said port being approximately centrally of the area within the flange, the outer internal portion of the wall being threaded, a cylindrical body insertible within the flange, said body having an outer portion threaded to engage the threads of the flange, the end of the body within the flange being adapted to contact with the straps, the opposite end of the body being provided with a closure having an opening therein 55 and having a channel in a wall of the opening, a piston within the body, a stem carried by the piston projecting through the opening of the closed end of the body, an expansible spring within the body embracing the stem 60 and interposed between the closed end of the body and the piston and a lug projecting from the stem adapted to pass through the channel in the wall of the opening of the closed end of the body.

In testimony whereof I have signed my name to this specification in the presence of two subscribing witnesses.

OTIS ALLEN.
